UNITED STATES PATENT OFFICE.

JOHN W. THOMPSON, JR., OF DRAKESVILLE, IOWA.

BURGLAR ALARM.

Application filed April 15, 1922. Serial No. 553,148.

To all whom it may concern:

Be it known that I, JOHN W. THOMPSON, Jr., a citizen of the United States, residing at Drakesville, in the county of Davis and 5 State of Iowa, have invented new and useful Improvements in Burglar Alarms, of which the following is a specification.

The object of this invention is to provide means for firing a cartridge if a burglar 10 should attempt to enter a window or door of a building so as to alarm the occupants and scare off the burglar.

Another object of this invention is to provide means for closing an electric circuit to 15 an alarm or the like by the opening of a window or door.

This invention also consists in certain other features of construction and in the combination and arrangement of the several 20 parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a diagrammatic view of the 30 invention.

Figure 2 is a vertical sectional view of the device in operative position. Figure 3 is in an elevation partly in section of the latch means for holding the device in operative 35 position, and Figure 4 is a perspective view of one of the elements embodied in the invention.

In these views 1 indicates a casing which is placed in any desired part of the building 40 and which is preferably of square shape in cross section. A block 2 is placed in the casing and a cylinder 3 passes through the block with its upper end projecting from the block, this end being screw threaded to receive a cap 4. The cylinder 3 is formed to receive an ordinary blank shot gun shell and the cap is provided with a firing pin 5 which is normally held in raised position by a spring 6. The cartridge is inserted after 45 the cap has been removed and then the cap is replaced so that the firing pin will be over the cap of the cartridge. The lower part of the casing is provided with holes 7 for the escape of the gases. A rod 8 passes through 50 a hole in the top of the casing and a weight 9 is attached to the lower end of the rod,

this weight being adapted to strike the firing pin to press the same against the cartridge to explode the same. The weight is normally held in raised position by means 60 of a trigger 10 which is pivoted to the top of the casing and has its pointed end engaging a recess 11' in the rod 8. When the trigger is moved out of the engagement with the rod the weight will fall and thus explode 65 the cartridge. In falling the weight will strike one end of a pivoted arm 11 which has its other end connected by a link 12 with the lever 13 of a knife switch 14. Thus this switch will be closed by the falling weight 70 so as to complete the circuit of the lighting system of the building or an alarm 15 which may be of any type and which may be located at any desired place.

A wire or other flexible connection 16 75 connects the cable with a bell crank 17 and other connections 18, which are secured to bell cranks 19, lead from the bell crank 17 to the windows and doors of the building, the connections which are fastened to the 80 windows and doors being so arranged that when the window or door is opened the connections will be pulled so that the trigger will be released from the rod and thus permit the weight to fall upon the cartridge. 85 The falling weight will also actuate the switch to close the electric circuit which may include the lights of the building so that these lights will go on and thus act to scare off the burglar. Of course an electric alarm 90 may also be included in the circuit and this alarm may be placed in any desired position in the building or in another building.

The invention may be used in all kinds of buildings such as stores, public and private 95 garages, ware houses and the like.

It is thought from the foregoing description that the advantages and novel features of my invention will be readily apparent.

I desire it to be understood that I may 100 make changes in the construction and in the combination and arrangement of the several parts, provided that such changes fall within the scope of the appended claim.

What I claim is:—

A device of the character described comprising a casing, a casting arranged in the casing and provided with a bore, a cartridge holding tube arranged in the bore, a cap 110 removably arranged upon one end of the cartridge holding tube, a spring pressed firing pin received in the cap and extending

vertically in the casing, a plurality of guide rods connected with the casting and the upper end of the casing, a weight slidably mounted on the guide rod, adapted to engage the 5 firing pin to detonate the cartridge contained in the cartridge tube, a rod carried by the weight and extending through the top of

the casing and a pivoted latch carried by the casing and normally engaging the rod to hold the weight in an elevated position, and means for disengaging the latch from the rod to permit the weight to fall.

In testimony whereof I affix my signature.

JOHN W. THOMPSON, JR.
